Primary Examiner — Richard Kearney

(57) **CLAIM**

The ornamental design for a folding gift box with ribbon, as shown and described.

DESCRIPTION

FIG. 1 is a front, top perspective view of a folding gift box with ribbon showing my new design;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof;
 FIG. 7 is a bottom plan view thereof; and,
 FIG. 8 is a perspective view of the folding gift box, shown separately without the ribbon, in an unfolded configuration.
